Attorney

UNITED STATES PATENT OFFICE.

FRANK H. LEHECKA, OF CHICAGO, ILLINOIS, ASSIGNEE TO TAYLOR-WHARTON IRON AND STEEL COMPANY, OF HIGH BRIDGE, NEW JERSEY, A CORPORATION OF NEW JERSEY.

RAIL CLAMP.

Application filed December 3, 1925. Serial No. 72,908.

My invention relates to rail clamps for use with steam shovels and other machines which are moved on rails, the office of the clamp being to prevent casual movement 5 of the machine along the rails while it is performing its regular work.

Objects of the invention are to provide a rail clamp of the integral unit construction type so as to avoid handling of separate parts; to provide a clamp instantly applicable to the rail head and constructed to take the impact of railroad wheels and to tighten rather than loosen under a series 10 of impacts; and to provide a clamp self-adaptable to the different clearances encountered with rails varying in size.

In its preferred form the invention is embodied in a body member of the integral type, including an overhead lug or guide 20 and depending lugs adapted to grip the underside of the rail head, the member being applied to the rail by manipulation through an angle of 45° and then swinging it parallel to the rail; one end of the body being 25 shaped to conform to the periphery of the wheel and the other end being bifurcated for the reception of a pivoted tightening device operating against the tread of the rail and of such nature that its tightening action 30 is accelerated by impact or pressure of the wheel against the body member.

My improved safety clamp is illustrated in the accompanying drawing, wherein

Figure 1 is a side elevational view of the 35 clamp applied to a rail.

Figure 2 is an end view.

Figure 3 is a bottom plan view.

Figure 4 is a detail of an underhead gripping device.

According to my invention the body member 5 is a one-piece casting, preferably of manganese steel. It is constructed with a terminal overhead lug or guide 6 and with a pair of depending lugs 7 and 8 having 40 inwardly directed terminals 9 shaped to fit the underside of the rail head and having serrated gripping faces 10. By disposing

the member 5 at the proper angle it can readily be applied to the rail, the underslope 11 of the body making for clearance 50 which enables the overhead lug or guide 6 to slip over the head of the rail and thus bring the clamp and rail in parallelism. To facilitate the application of the clamp the opposed corners of the underhead gripping 55 lugs are cut away as at 12.

One end of the body member 5 has a curved face 13 to fit the wheel; the other end is divided by a vertical slot to form spaced side walls or cheeks 14 for the reception of the tightening device. The latter is an eccentric lever 15 mounted between the cheeks on a pivot pin 16. The swinging lever is so designed that for each 10° divergence from a point approximately 40° 60 from a perpendicular position the distances increase from center of pin to edge of lever thus enabling the clamp to take care of clearances for different sized rails.

As thus constructed and arranged it will 70 be apparent that instead of losing its grip and sliding along the rail under repeated jolt or impact the tightening action of the clamp will if anything be increased.

Having described my invention, I claim: 75

1. A rail clamp body consisting of an integral casting having a sloping bottom to provide rail clearance and having depending lugs with gripping terminals and a lining up lug or guide, the depending lugs 80 having their opposed corners removed, to facilitate the application of the clamp.

2. A rail clamp of the straddle type having a chock or wheel engaging portion and a bifurcated portion, and a lever pivotally 85 mounted in the latter and having an eccentric portion to engage the tread of the rail and whereof the tightening action is augmented by repeated impact or pressure of the wheel against the clamp. 90

In testimony whereof I affix my signature.

FRANK H. LEHECKA.
